FOLDING BED OR CAMP STRETCHER

Archibald Calder, North Brighton, near
Melbourne, Victoria, AustraliaApplication August 20, 1942, Serial No. 455,455
In Australia July 29, 1941

4 Claims. (CL. 5—117)

This invention relates to improvements in folding beds of the character known as camp beds or stretchers. More specifically, it is directed to the provision of improvements in folding beds of the type having a top formed of jute, canvas or like flexible material secured at its opposite sides to longitudinal rails, each of which is formed of two hingedly connected sections for the purpose of folding, the said top being mounted upon and detachably secured to a plurality of bearers which are arranged transversely and rest directly upon the floor or ground.

The principal object of the invention is to provide an improved folding bed or camp stretcher which is comfortable and serviceable and will meet the requirements of economy in constructional costs, ease of assembly and dismantlement, and smallness of space occupied by the bed after it has been dismantled and its components folded together for storage or transport.

A folding bed constructed according to the invention has at each side a plurality of longitudinally aligned and suitably spaced posts which at their upper ends are rigidly fastened by detachable stayed joints to the longitudinal rails of the bed top, and at their lower ends are securely, but detachably, fastened to the bearers that rest upon the floor or ground. Moreover, the posts are provided with obliquely disposed stays which at their upper ends are pivotally secured to upper end portions of said posts and at their lower ends pivotally fastened to the transverse bearers. Thus, the bed structure is adequately stayed and the bed top is very firmly supported so as to resist tendency of inward collapsing movement. When the posts have been detached and the bed is being set up or is being dismantled, the posts are free to swing pivotally on the oblique stays, and the latter may have pivotal movement on the transverse bearers.

The invention is illustrated by the accompanying drawings to which reference is now made for the purpose of a detailed description.

Figs. 1 and 2 are views in side elevation and end elevation, respectively, of a folding camp bed according to the invention.

Figs. 3 and 4 are fragmentary views in end elevation and side elevation, respectively, illustrating means for rigidly but detachably connecting the upper ends of the side posts to the longitudinal rails of the bed top, and for detachably connecting the lower ends of the posts to the transverse bearers in such manner as will provide resilient mountings for said posts to impart springiness to the bed top.

Fig. 5 is a detail view in end elevation illustrating a means for detachably connecting the lower ends of the side posts to the transverse bearers, according to which the posts are non-resiliently mounted on the bearers.

Figs. 6 and 7 are detail views in end elevation and side elevation, respectively, illustrating alternative means for detachably connecting the lower ends of the side posts to the transverse bearers so as to provide resilient mountings for said posts.

Figs. 8 and 9 show in end elevation and side elevation, respectively, modified means for rigidly but detachably connecting the opposite ends of the side posts to the longitudinal rails of the bed top and the transverse bearers.

Figs. 10 and 11 are detail views showing in end elevation and side elevation, respectively, modified means for rigidly but detachably connecting the lower ends of the side posts to the transverse bearers.

Figs. 12 and 13 are detail views in end elevation and in side elevation, respectively, illustrating a modification according to which the lower ends of the side posts are pivotally secured to the transverse bearers and the oblique stays are rigidly but detachably fastened at their lower ends to said bearers.

The folding camp bed has its top composed of a length of jute, canvas or like flexible material 2 which is secured at its opposite sides to longitudinal rails 3 preferably made of timber and each formed in two sections placed end to end and hingedly connected together by a hinge plate 4 of suitable type. The camp bed may have a hingedly fitted head section (not shown) adapted to be raised and lowered relatively to the other portion of the bed top and to be retained in an elevated position according to the adjustment selected for the comfort of the user.

Transverse bearers 5, preferably made of timber, are provided and rest directly upon the floor or ground in parallel spaced arrangement corresponding to the head, the middle and the foot locations of the bed. The bed top is mounted upon said bearers by the provision of three wooden posts 6 at each side. These posts usually are relatively short in order that the bed top will be close to the floor or ground level as is desirable when folding beds or camp stretchers are intended for use in tents and other places having space restrictions.

The side posts 6 are rigidly but detachably fastened at their upper ends to the rails 3 of the bed top. For this purpose sockets are formed

in the underneath portions of said rails to snugly accommodate dowels 7 formed at the upper ends of the posts, and stay members 8 are secured to the rails at 9 on opposite sides of the dowel and socket joints and depend at suitable distance beneath the rails.

Each of these stay members has at its lower end a catch 10 positioned to coincide with the longitudinal centre line of the relative dowel and socket joint, and it is adapted for detachable interlocking engagement with a fastening element fitted rotatably to the post. The preferred form of stay member 8 is that illustrated in Figs. 1 to 4 and Figs. 12 and 13, consisting of a substantially V-shaped device formed of wire and having its apical portion shaped to form a V-shaped catch 10. The rotatable fastening element for the said stay member consists of a wire turn-pin 12 rotatably fitted in a hole drilled in the upper end portion of the post and having a lever arm 13 which is bent at an obtuse angle to the horizontal portion and is suitably spaced from the post as is seen clearly in Figs. 3 and 12. In fitting a post 6 to a rail 3 of the bed top, the lever arm 13 is turned upwardly to vertical position and the post dowel 7 is inserted into the rail socket while the lever-arm 13 is passed through the branches of the V-shaped stay member 8. The lever arm is then turned downwardly so that its angular portion 14 wedges into the V-shaped catch 10 of said stay member whereby the post and rail are rigidly clamped together. To release the post from the rail, it merely requires the lever arm 13 to be upwardly turned into vertical position to release the clamping pressures exerted between the two components which are then readily separable.

A modification of the means hereinbefore described for detachably fastening the upper end portion of a side post 6 to a longitudinal rail 3 of the bed top is illustrated in Figs. 8 and 9. In these views 15 designates a stay plate of suitable shape which is secured at 16 to the rail on opposite sides of the dowel and socket joint and depends beneath the rail. This plate 15 has at its lower end portion a vertical open-ended slot 17 with rounded protuberances 18 on opposite sides of said slot.

This vertical slot is in a position coinciding with the longitudinal centre line of the dowel and socket joint when the post and rail are assembled, and it is adapted to fit about a bolt 19 which is passed through the upper end portion of the post. A wing-nut 20 is fitted on the bolt 19 and is adapted to be tightened against the stay plate 15 to rigidly lock the post and rail together. Owing to the impingement of the wing-nut against the protuberances 18 when it is tightened against the stay plate, liability of the said wing-nut working loose under strains imposed upon the bed top is minimised. The outer end of the bolt can be burried to prevent accidental detachment and loss of the wing-nut.

An oblique stay 21 extends between the upper end portion of each side post 6 and its relative bearer 5. This oblique stay is pivoted at 22 to the post, and in the constructions illustrated in Figs. 1 to 4 and Figs. 8 and 9 its lower end is pivoted at 23 to the bearer. Each of the oblique stays 21 may consist of a single bar of flat metal. Alternatively, it may consist of two flat metal bars in parallel space arrangement which are secured at their upper ends to opposite sides of the post 6 and to opposite sides of the bearer 5. Further-

more, each of said oblique stays may be formed of a bar of channel-section metal which is connected at its opposite ends to opposite sides of a post 6 and opposite sides of the relative bearer 5.

5 The ends of the transverse bearers 5 extend laterally beyond the side posts 6 which are mounted thereon, and said side posts have an outward inclination from their lower ends in order that when the components have been assembled in the setting up on the bed the fabric 2 of the bed top will be suitably tensioned, and any tendency of inward collapsing movement of the longitudinal rails 3 when a heavy weight is placed on the bed top will be effectively checked.

10 15 A U-shaped catch 24—see Figs. 1 and 4—is rigidly fastened at 25 to the lower end portion of each side post 6 and it extends below said post. The ends of the transverse bearers 5 are tapered and secured to the upper surface of their tapering end portions are clip devices adapted to engage and retain the catches 24. Each of said clip devices comprises a substantially flat plate 11 formed of spring metal which is riveted at 26 to the bearer 5 and is separated therefrom by a spacer 27. Projecting downwardly from the free end portion of the spring plate 11 is a rounded stud 28. When the camp bed is being set up and inward pivotal movement is imparted to a post 6, the catch 24 enters the jaw formed between the spring plate and the top of the bearer and contacts the stud 28 thereby slightly elevating said spring plate and permitting the inward travel of the catch until stopped by the outer end of the spacer 27. Upon return of the spring plate to its 20 normal position the catch 24 is held between the spacer 27 and the stud 28 as clearly illustrated in Fig. 3. The outer end of the spring-plate is preferably fashioned as a finger-piece 29 to facilitate its elevation to release the catch 24 from the bearer 5 when the bed is being dismantled. In order to eliminate risk of accidental disengagement of the post 6 from the bearer 5 in the event of very heavy strains being imposed upon the bed top, a safety latch 30 may be pivoted to the bearer at 31 and is adapted for engagement with the outer end of the spring plate 11 for the purpose of restraining the latter against any upward movement such as might permit unintentional release of the catch 24 from the spring clip with which it was engaged.

50 The strength of the spring clips provided at the ends of the transverse bearers 5 can be regulated by adjustment of clamps 32 which embrace and are longitudinally slidable over the spring plates 11 and the ends of the bearers, each being locked in selected position by a setscrew 33. To accommodate the slideable clamps, the outer end portions of the bearers are suitably recessed on their underneath surfaces as indicated by 34 in Fig. 3. It will be obvious that instead of the single flat plate 11 of spring metal which has been hereinbefore described, a laminated spring unit (not shown) may be used, the said unit being riveted or otherwise fixed to the upper surface of a transverse bearer at the outer end portion thereof. The hereinbefore described means for detachably connecting the side posts 6 to the transverse bearers 5 provides a resilient mounting of the said posts which support the bed top and means for conveniently regulating the permitted degree of resilience.

70 Fig. 5 illustrates a spring clip secured on the end of a bearer 5 and adapted to engage the catch 24 which is fastened to the lower end of a

side post 6 without providing a resilient mounting for said post. In this construction of clip, the spring plate 11 is provided with a downwardly projecting rounded stud 28 and at its outer end a finger-piece 29 for the purposes hereinbefore explained, and it has on its underneath surface a plate 35 of lesser length but of non-springy metal. The two superimposed plates are mounted on a spacer 27 and they are secured to the tapering end of the bearer 5 by rivets 36, the outer end of said spacer functioning as a stop for the catch on the post.

A modified means for detachably fastening a side post 6 to a transverse bearer 5 is illustrated in Figs. 6 and 7 wherein 37 designates a flat plate of spring metal secured by rivets 38 to the bearer. This plate 37 has at one end a hook 39 provided with an extension 40 for use as a finger-piece. The post 6 is bevelled at its lower end in order that when mounted on the bearer to provide a support for the bed top it will rest flatwise on top of the metal plate 37. A rectangular frame 41 is pivotally supported by a tubular boss 42 on a metal plate 43 secured to one side of the post 6 by rivets or other fastenings 44. When the bed is being set up and the post is swung into position on the bearer the lower member of said frame 41 is automatically engaged with spring action by the hook 39 to hold the post in position. When it is required to dismantle the bed, upward pressure is applied to the finger-piece 40, whereby the spring plate 37 will be elevated sufficiently to release the frame 41 from its engagement with the hook 39 and thereby release the post. Although the plate 43 pivotally supporting the frame 41 is illustrated as being secured to the inner side of a post 6, it will be understood that it could be secured to the outer side of said post, in which case the spring plate 37 having the hook 39 would be reversed in its position on the bearer 5.

According to the modification illustrated by Figs. 8 and 9, the lower ends of side posts 6 are fitted into seating recesses formed in the upper surface of the bearers 5. Owing to the outward inclination of said posts, the seating recesses are of tapering formation. Each of said posts is rigidly but detachably fastened to its relative bearer by a wire stay 45 of substantially inverted V-shape secured on opposite sides of the seating recess and having at its apical portion an inverted V-catch 46 adapted to engage a turn-pin 47 fitted rotatably in the lower end portion of the post and furnished with a lever arm 48.

The wire stay 45 and the turn-pin 47 are of the same character and function in identical manner as the stays 8 and turn-pins 12 employed for detachably fastening the upper ends of the posts 6 to the longitudinal rails 3 of the bed top as hereinbefore described with reference to Figs. 1 to 4 and Figs. 8 and 9.

In lieu of the hereinbefore described U-shaped catch 24 provided at the lower end of each side post 6, there may be used two flat plates 49—see Figs. 10 and 11, which are secured by rivets 50 on opposite sides of the post and extend below its lower edge. These plates have inwardly projecting studs or tangs 51 which are engageable in a hole 52 drilled in the end of a bearer 5. A screw 53 is passed through the plates 49, and a wing-nut 54 fitted on the said screw is adapted to be tightened against one of said plates 49 to lock the post to the bearer. When the wing-nut has been unscrewed, said plates can be readily

sprung apart to release their studs or tangs 51 from engagement in the hole 52 and thus detach the post from the bearer.

According to the modified means for connecting the lower end portion of a side post 6 with its relative bearer 5 illustrated in Figs. 12 and 13, the post is pivotally fastened to the bearer instead of being adapted for detachable rigid connection thereto, and the corresponding end of the oblique stay 21 is adapted for detachable fastening to the said bearer instead of being pivoted thereto as has been hereinbefore described. In these figures of the drawings 55 designates two flat metal plates which are riveted to the lower end of the post 6 and extend below the bottom of said post to provide a jaw to receive and snugly accommodate the end of the bearer 5.

A pivot pin 56 is passed through the plates 55 and through the bearer. The oblique stay 21 is pivoted at its upper end to an upper portion of the post 6, and at its lower end it is slotted at 57 to take over or accommodate a screw or bolt 58 which is passed through the bearer 5 and is fitted with a wing-nut 59 adapted, when tightened, to impinge against protuberances 60 formed on opposite sides of the slot 57 to rigidly fasten the stay in such manner that it will be maintained in its correct relationship with the post 6 when the bed has been set up and is in use.

It will be observed that the lower end of the oblique stay 21 and the fastening devices 58-59 in the modification illustrated in Figs. 12 and 13 are similar in construction to the lower portion of the stay plate 15 and its fastenings 19-20 hereinbefore described for detachably securing the upper end of a side post 6 to a longitudinal rail of the bed top, the same being illustrated in Figs. 8 and 9.

In all forms of the invention the side posts 6 supporting the bed top are rigidly, but detachably, secured at their upper ends to a longitudinal rail 3 of said bed top by means of a combined stay and fastening device and oblique stays which are fastened at their lower ends to transverse bearers whereon said posts are mounted are pivotally connected at their upper ends to upper end portions of said posts. This construction permits the bed to be erected and to be dismantled with ease and convenience, and enables the components of the dismantled bed to be folded into small compass for storage or transport.

What I do claim is:

1. In a folding camp bed equipped with transverse bearers adapted to rest upon the floor in parallelly spaced arrangement, rigid longitudinal rails, a bed top secured to said rails, a series of posts provided at the opposite ends of said bearers fastened at their upper ends to said longitudinal rails and a series of oblique stays provided between said bearers and the upper end portions of said posts pivotally attached to the latter; a series of pivotal connecting means fastening predetermined fixed points of said oblique stays turnably to predetermined fixed points of the corresponding bearers, spring clips secured to the opposite ends of said bearers, and catches at the lower ends of said posts for detachable and releasable engagement by said spring clips.

2. In a folding camp bed according to claim 1, each of said catches at the lower ends of said posts consisting of a U-shaped member and each of said spring clips secured at the ends of said bearers comprising a spring plate having on its underneath surface a stud for detachable and releasable engagement by said U-shaped mem-

ber and a stop to limit the inward movement of said U-shaped member.

3. In a folding camp bed according to claim 1, each of said catches at the lower ends of said posts consisting of a U-shaped member and each of said spring clips secured to the opposite ends of said bearers comprising a spring plate having on its underneath surface a stud for detachable and releasable engagement by said U-shaped member, a stop to limit the inward movement of said U-shaped member, and a slidable clamp

locked by a set screw for regulating the strength of said spring plate.

4. In a folding camp bed according to claim 1, each of said catches at the lower ends of said posts consisting of a rectangular frame pivoted to one side of the post and each of said spring clips secured to the opposite ends of said bearers consisting of a spring plate having at its free end a hook-shaped member for interlocking engagement with said pivoted frame.

ARCHIBALD CALDER.
